(57) **CLAIM**

The ornamental design for a housing for volatile dispenser, as shown and described.

DESCRIPTION

In a preferred embodiment, the nature of this product is as a housing for an electric heat activated dispenser of volatile actives, such as insecticides and fragrances.

FIG. 1 is a right, top, frontal perspective view of a housing for a volatile dispenser embodying our new design;

FIG. 2 is a right side elevational view thereof, the left side being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right, top, frontal perspective view of a second embodiment of our new design;

FIG. 8 is a right side elevational view thereof, the left side being a mirror image thereof;

FIG. 9 is a front elevational view thereof;

FIG. 10 is a rear elevational view thereof;

FIG. 11 is a top plan view thereof;

FIG. 12 is a bottom plan view thereof;

FIG. 13 is a right, top, frontal perspective view of a third embodiment of our new design;

FIG. 14 is a right side elevational view thereof, the left side being a mirror image thereof;

FIG. 15 is a front elevational view thereof;

FIG. 16 is a rear elevational view thereof;

FIG. 17 is a top plan view thereof; and,

FIG. 18 is a bottom plan view thereof.

The broken line representations of plug environment in FIGS. 7-8, 10-14 and 16-18, internal and lower housing features in FIGS. 7-8, 10-14 and 16-18, seam lines in FIGS. 7-10 and 13-16, lip features in FIGS. 7-9 and 11-12, and rib features in FIGS. 13-18, are for purposes of illustration only, and form no part of the claimed design.
